L. PHILLIPS

NECKTIE PRESSER

Filed Jan. 8, 1926

WITNESS:

Gerald Hennessy

L. G. Phillips

UNITED STATES PATENT OFFICE.

LZ PHILLIPS, OF WASHINGTON, DISTRICT OF COLUMBIA.

NECKTIE PRESSER.

Application filed January 8, 1926. Serial No. 80,034.

To all whom it may concern:

Be it known that LZ PHILLIPS, citizen of the United States, residing at 630 10th Street NE., Washington, District of Columbia, has invented certain new and useful Improvements in Necktie Pressers, of which the following is a specification.

My invention relates to necktie pressing devices.

10 The primary object of my invention is to press neckties which have become wrinkled in use.

Another object is to remove the wrinkles preparatory to the pressing, with a minimum of time and effort.

15 In the accompanying drawing which illustrates my invention:—

Figure 1 is a perspective view showing the invention in use.

20 Figure 2 is a section on the line 2—2 of Figure 1.

Similar reference characters refer to similar parts through the several views.

The numerals 1 and 2 indicate two blocks

25 which comprise the pressing elements; these are held in operative position by the two bolts 3. Thumb nuts 4 and washers 5 are provided on the two bolts with which the blocks 1 and 2 may be brought to bear on

30 the necktie N.

The means for removing the wrinkles comprises a clamp 6 which is similar in action to the clamp on a mouse trap; the axle portion of this clamp designated 7 is held to the upper block 1 by eye screws 8 while the lower part of the clamp is provided with two rollers 9 which converge downwardly. These rollers 9 are caused to bear against the end of the lower block 2

by a spring 10, which has two coils 10' and 40 a central loop 11 which is fastened to the block 1 by a screw 12. The two ends of the spring bear on opposite sides of the clamp 6.

To operate unscrew the two blocks until they are about three quarters of an inch 45 apart, dampen the tie on the back where the wrinkles are, stand the blocks on end with the rollers up, pull back the rollers and drop the small end of the tie between the blocks the right side up, now lay the blocks down 50 on the corner of a table or dresser, allow the blocks to come together, (don't screw down) let the rollers down, pull the tie through to where the wrinkles are, now with one hand guide the rollers so that they are in the center 55 of the tie and with the other hand pull the tie through until the wrinkled part is within the blocks, screw the blocks together a little, not too tight, just enough to keep the tie in shape, let stand two to three hours or better 60 still over night, it takes about one minute to put the tie in and one-half minute to take it out.

I claim:—

1. A device for the purpose set forth, comprising pressing blocks held in operative position by bolts, means on said bolts for clamping the blocks together, diverging rollers yieldably held against one of the blocks. 65

2. A device for the purpose set forth, comprising pressing blocks held in operative position by clamping bolts, diverging rollers yieldably held against one of the blocks, a double spring bearing against the member carrying the rollers, the center of said 70 spring secured to one of the blocks. 75

In testimony whereof I affix my signature.

LZ PHILLIPS.
